L. B. MANSON.

LIGHTING SET.

APPLICATION FILED MAR. 30, 1921.

Patented Aug. 29, 1922.

Leau B. Manson Inventor
By his attorneys William & Putchard

UNITED STATES PATENT OFFICE.

LEON B. MANSON, OF BROOKLYN, NEW YORK, ASSIGNOR TO FRANCO ELECTRIC CORPORATION, A CORPORATION OF NEW YORK.

LIGHTING SET.

1,427,489.

Specification of Letters Patent. Patented Aug. 29, 1922.

Application filed March 30, 1921. Serial No. 457,091.

To all whom it may concern:

Be it known that I, LEON B. MANSON, a citizen of Russia, and a resident of Brooklyn, county of Kings, State of New York, 5 have invented certain new and useful Improvements in Lighting Sets, of which the following is a specification.

My invention relates to lighting sets such as are used, for example, in the ornamentation of Christmas trees, or other objects adapted to be illuminated by a number of small lights strung or wound about the same. In the present devices of this nature on the market much difficulty is experienced in enlarging the layout, or adding additional sets, because requiring the use of a junction box and the use of tools in demounting said junction box for the addition of more sets.

An object of this invention is to provide 20 a simple and inexpensive device of the above type which shall overcome the aforementioned difficulties and which is especially adapted to be easily connected with other devices of a similar nature and for a similar 25 purpose.

To these and other ends my invention consists in certain arrangements and combination of parts as will be more particularly pointed out in the claims appended to this 30 specification.

Referring to the drawing, Figure 1 shows the first of my lighting sets.

Figure 2 represents one of any number of additional sets which are adapted to be 35 readily connected with the first mentioned set shown in Figure 1.

The numeral 10 indicates some conventional form of electrical connector; for example, an ordinary plug adapted to be 40 screwed into a lamp socket. Secured within and in electrical contact with the plug 10 are a plurality of leads or conductors 11 and 12 of appropriate length terminating at their other end in a member 13 of an electrical 45 connector or quick attachable couple of some appropriate form. Another lead or conductor 14 is bridged across both the leads 11 and 12 and the connecting members 10 and 13 and is adapted to supply current to some 50 form of translating device, for example, the miniature lamps 15 shown in the drawing as being connected in series. That is, the conductors 11 and 14 are in contact within the plug 10, while the conductors 12 and 14 are

in contact within the connector 13. When 55 additional lighting sets are to be used on the Christmas tree, or other object to be illuminated, one or more sets of the type illustrated by Figure 2 are adapted to be connected with the set shown in Figure 1. 60 These sets are similar to that shown in Figure 1 in having leads 11^a and 12^a connecting member 13^a, conductor 14^a and lamps 15^a, but differ from the first set in having a connecting member 16 in place of plug 10 which 65 member 16 is adapted to be readily joined with the connector 13 by inserting the projecting prongs 17 within the conducting recesses in the member 13. An additional set, the duplicate of that shown in Figure 2, is 70 adapted to be connected to the member 13^a in the same manner. If desired, an insulating cap of appropriate form may be provided for the connector 13 in order to prevent an accidental short-circuit of the terminals, or the end face 18 of this connector 75 may if desired be countersunk for the same purpose.

Among the advantages of the present invention may be enumerated the saving in 80 wire which results from bridging the conductor 14 across both the leads 11 and 12 and the connectors 13 and 10, and doing away with the necessity of having an additional 85 return conductor from the last lamp 15 back to the plug 10. An especially noteworthy 90 feature is the ease of manipulation required when additional lamps are to be electrically connected in circuit, doing away with the necessity of having the more expensive junction boxes and also avoiding the requirement 95 for tools which had been previously necessary to connect such additional circuits to the junction boxes. A further advantage resides in having the wiring continuous and 100 in doing away with the necessity for return leads from the last lamp of the last set to the junction box or other source of current, the different sets when connected in the manner outlined extending in prolongation. 105 This last mentioned feature will be the better appreciated when it is understood that the additional sets shown by Figure 2 may all be made of standard length and yet enable the lighting sets to reach any desired 110 height in the tallest Christmas tree. Mention may also be made of doing away with the mechanical overload frequently given to

the binding screws in the junction box when a large number of additional lighting sets are to be used.

I claim:

- 5 1. In a Christmas tree lighting set, the combination with a quick attachable connector, of a pair of leads in contact therewith, a second connector in contact with said leads, and a plurality of lamps joined in series and connected to one side of the leads within the first mentioned connector and to the other lead within the second mentioned connector.
- 10 2. The combination with an electric connector, of a plurality of conductors adapted to carry current for said connector, a complementary connector in contact with the end portion of said plurality of conductors remote from the first mentioned conductor, and a flexible conductor bridged across both

said plurality of conductors and joining said connectors and adapted to supply current to a translating device in circuit therewith, said connectors being adapted to engage directly with one another.

25

3. A miniature lighting set comprising in combination a detachable connector and a pair of flexible insulated conductors secured thereto, a second detachable connector adapted for cooperation with said first mentioned connector, said pair of conductors terminating in said second connector, and a plurality of lamps in series, joined by a flexible conductor and connected with each of the detachable connectors and in shunt with said 30 pair of flexible conductors.

In testimony whereof, I have affixed my signature to this specification.

LEON B. MANSON
